(57) **CLAIM**

The ornamental design for an ice cream dispenser, substantially as shown and described.

DESCRIPTION

FIG. 1 is a perspective view of an ice cream dispenser showing our design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is an underneath view thereof.

The broken lines represent the bounds of the claimed design while all other broken lines are directed to environment and are for illustrative purposes only; the broken lines form no part of the claimed design.
